UNITED STATES PATENT OFFICE

GUSTAV PIELSTICK, OF AUGSBURG, GERMANY, ASSIGNOR TO MASCHINENFABRIK AUGSBURG-NÜRNBERG, A. G., OF AUGSBURG, GERMANY, A CORPORATION OF GERMANY

ENGINE CYLINDER

Application filed April 15, 1929, Serial No. 355,175, and in Germany April 23, 1928.

This invention relates to engine cylinders, and more particularly to cylinders for engines of the two cycle type.

One object of the invention is the provision of a cylinder for combustion engines comprising a cylinder portion forming part of the working cylinder and an attached end portion which has a wall tapering gradually in cross section towards the first mentioned cylinder portion and providing a part of the working cylinder.

Another object of the invention is the provision of a cylinder for an internal combustion engine having an intermediate portion and an end piece in both of which the piston is adapted to reciprocate, the end piece being attached to the intermediate portion by means of a flanged cooling jacket provided around the end piece.

Other objects and advantages of the invention will be apparent from the following description and from the accompanying drawing, in which the single view is a longitudinal section of a cylinder embodying the present invention.

The cylinder shown in the drawing, which illustrates the invention as applied to a double acting two cycle internal combustion engine, comprises an intermediate cylinder portion *c* formed preferably as a metal casting and providing the intermediate part of a working cylinder. As the invention is herein set forth as applied to an engine of the Diesel type operating with fuelless injection and having scavenging and exhaust holes in the cylinder wall, the intermediate portion *c* is provided with scavenging slots *a* and exhaust slots *b* for both sides of the acting cylinder. A cooling chamber wall *d* surrounds the portion *c* of the working cylinder, this cooling wall *d* being preferably cast with portion *c* of the cylinder.

The intermediate cylinder portion *c* terminates in flanges *e* upon which rest end pieces or covers *f*, the latter having outwardly extending flanges *g* at their inner terminal portions which rest upon the flanges *e* of portion *c*. The covers or end pieces *f* are approximately flat at the end of the combustion chambers providing approximately flat

cylinder heads which are of sufficient thickness and suitably reinforced to withstand the heat conditions and the high pressures which obtain during operation. Extending inwardly from the cylinder head of each end piece *f* is a wall having a cylindrical bore, this wall being flush with the inside of the cylinder portion *c* and thus forming a part of the working cylinder. The wall tapers gradually in cross section from the cylinder head to the intermediate cylinder portion *c*, the inner portions of this wall being quite thin as they do not need to withstand the exceedingly high pressures obtaining when the piston is at the end of its stroke and as there is consequently less bursting tendency at the inner portions of this wall. This construction, however, provides for a light cylinder head end piece, yet one which is of sufficient strength to withstand the pressures and strains imposed upon it. Moreover, by the reduction of the thickness of the inner portions of the cylinder end piece cooling of the frictional wear surfaces which are in frictional engagement with the piston and piston rings is greatly facilitated and such surfaces operate at a cooler temperature which aids in efficient operation. Preferably the cross sectional thickness of the wall of the end pieces *f* is suitably coordinated with the pressures and strains to which the particular portion of the wall is subjected in operation, the inner portions of the wall being thinner as the combustion pressure and wall temperatures are gradually decreased from the combustion chamber towards the intermediate part of the cylinder.

The connection of the two end pieces *f* to the intermediate cylinder portion *c* is preferably effected by means of cooling jackets *h* surrounding the respective end pieces *f*. These cooling jackets are each shaped in correspondence with an end piece *f*, and spaced therefrom in such a way as to provide a cooling chamber through which water or other suitable cooling liquid may be circulated. At one end of the cylinder the end piece *f* is provided with a throat *f*¹ which receives the fuel injecting means, the opposite end piece *f* having a corresponding throat *f*² receiving the

stuffing box. The cooling jackets have suitable apertures receiving the two throats f^1 and f^2 .

On the inner end of each cooling jacket is an outwardly extending flange or rim h^1 which fits over and about the flange g of the end piece f . The cooling jacket flange h^1 is secured to the flange e of the intermediate cylinder portion by suitable attaching bolts (not shown), and the flange h^1 thus clamps the flange g of the cylinder end piece f between it and the cylinder portion c . Preferably the two opposite end pieces f of a cylinder are firmly clamped in place by through bolts interconnecting opposing cooling jackets and attaching them firmly together and thus securing the end pieces of the cylinder in place.

The cooling jackets h are connected to the cooling wall d of the intermediate cylinder by suitable connections i so as to form a cooling chamber extending from one end of the cylinder to the other so the cooling medium entering at the inlet j may flow through the entire cooling jacket, flowing out through the opening k .

While the form of apparatus herein described constitutes a preferred embodiment of the invention, it is to be understood that the invention is not limited to this precise form of apparatus, and that changes may be made therein without departing from the scope of the invention which is defined in the appended claims.

35 What is claimed is:

1. A cylinder for internal combustion engines comprising a cylinder portion forming a part of the working cylinder, and a separate end piece attached thereto, said end piece having a cylindrical bore providing the outer part of a working cylinder and an approximately flat cylinder head at the end of said bore, the wall of said end piece inwardly of the cylinder head gradually decreasing inwardly in cross section, and a cooling jacket around said end piece, said end piece and said jacket having abutting end flanges, the flange of the end piece being clamped between the flange of the jacket and the outer end of said cylinder portion.

2. A cylinder for double acting two cycle internal combustion engines comprising an intermediate cylinder portion and two end pieces which with said cylinder portion form a working cylinder, each end piece providing a substantially flat cylinder head and having a substantially cylindrical wall gradually decreasing in cross sectional dimensions inwardly of the cylinder head, and a cooling jacket around each end piece, each end piece and jacket terminating in outwardly extending flanges, the flange of the end piece being clamped between the flange of the jacket and the intermediate cylinder portion.

3. A cylinder for double acting two cycle

internal combustion engines comprising an intermediate cylinder portion and two end pieces attached thereto, said end pieces each providing a cylinder head and having an inwardly extending wall forming a part of the working cylinder, each end piece terminating in an outwardly extending flange, and a cooling jacket around each end piece, said jacket terminating in a flange, the flange on the end piece being clamped between the jacket flange and an end of said intermediate cylinder portion.

4. A cylinder for a two cycle internal combustion engine comprising a cylinder portion forming a part of the working cylinder, a separate end piece attached thereto said end piece having a cylindrical bore providing the outer part of the working cylinder and also providing a cylinder head at the end of said bore, the wall of said end piece inwardly of the cylinder head gradually decreasing inwardly in cross section, and a cooling jacket around said end piece, said end piece and said jacket having abutting end flanges, the flange of the end piece being clamped between the flange of the jacket and the outer end of said cylinder portion.

In testimony whereof I have affixed my signature.

GUSTAV PIELSTICK.
